Fig. 1.

Fig. 2.

Fig. 3.

Fig. 4.

Fig.5.

Fig.6.

FIG. 1 is a front perspective view of an adapter for a circuit breaker;

FIG. 2 is a front elevational view thereof;

FIG. 3 is a side elevational view thereof;

FIG. 4 is a bottom plan view thereof; and

FIGS. 5 and 6 illustrate a modification of my invention and FIGS. 5 and 6 show side elevational views of the two sides of the adapter for a circuit breaker showing my modified design, the other views of this embodiment being the same as shown in FIGS. 1 to 4.

The circuit breaker includes a portion which includes features shown in Design Pats. No. 206,006 and 203,271, and in the pending design patent application of Ralph B. Davis filed Dec. 2, 1969, Ser. No. 20,330.

The portions of the figures shown in broken lines are shown for illustrative purposes only.

I claim:

The ornamental design for an adapter for a circuit breaker, as shown and described.
